UNITED STATES PATENT OFFICE.

BURKARD ROSENBOAND, OF NEWARK, NEW JERSEY.

CASE OR BOX FOR MATCHES OR OTHER ARTICLES.

SPECIFICATION forming part of Letters Patent No. 634,543, dated October 10, 1899.

Application filed June 13, 1899. Serial No. 720,353. (No model.)

To all whom it may concern:

Be it known that I, BURKARD ROSENBOAND, a citizen of the United States, residing at Newark, in the county of Essex and State of New Jersey, have invented certain new and useful Improvements in Cases or Boxes for Matches or other Articles; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention has reference to improvements in cases or boxes such as are ordinarily employed for the carrying of matches, postage-stamps, or for jewelry or other like cases.

The object of this invention is to provide a novel construction of case or box which shall be very simple in its construction and to provide a novel construction of holding or locking catch therefor, all of which will be hereinafter fully set forth, and finally embodied in the clauses of the claim.

With these several objects in view my invention consists, essentially, in the novel arrangement of a pair of hinged leaves or cover-sections, one provided with a right-angled edge or wall, which forms a back, and a box-like receiving device arranged between said leaves or cover-sections, said receiving device having three sides thereof at the front and ends closed, but at the back, where it is fitted against the right-angled edge of one of said leaves or cover-sections, open, the whole thereby receiving the appearance of a book in miniature, the leaves or cover-sections of which may be provided with a covering of leather or other similar material.

My invention consists, furthermore, in such other novel arrangements and combinations of the parts comprising the box or case, as well as in the details of the construction thereof, all of which will be hereinafter fully described, and finally embodied in the clauses of the claim.

The invention is fully illustrated in the accompanying drawings, in which—

Figure 1 is a plan of my novel construction of case or box, and Fig. 2 is an edge or side

view of the same on an enlarged scale. Fig. 3 represents a plan or top view of the box or case embodying the principles of my invention, with the hinged leaf or cover sections represented in their open relation and illustrating the receiving device in its operative position. Fig. 4 is a vertical cross-section on an enlarged scale, said section being taken on line 4-4 in Fig. 1; and Fig. 5 is a longitudinal vertical section taken on line 5-5 in Fig. 3. Fig. 6 is a detail front view of the locking or holding parts connected with one of said leaf or cover sections and the edge of the said receiving device, the parts just about to be sprung together into their locked or holding engagement. Fig. 7 is a detail vertical section of the said parts in their locked or holding engagement one with the other. 9855 9860 9865 9870 9875 9880 9885 9890 9895 9900 9905 9910 9915 9920 9925 9930 9935 9940 9945 9950 9955 9960 9965 9970 9975 9980 9985 9990 9995 9999

At or near the central portion of the edge a^6 of the leaf or section a I have stamped out thereon a portion of the metal, so as to provide a hole or opening a^7 , preferably shaped in outline, as represented more particularly in Figs. 3, 6, 7, and 8, with the connecting portion or band-like part a^8 bent downwardly, as more clearly indicated in Figs. 6 and 7, so as to be arranged beneath the under surface

a^9 of said leaf or cover section a , as clearly indicated. When the box or case is to be used as a match-safe, then the said leaf or section a may be provided with serrations or 5 other suitable scratching-surface a^{10} . In order that the leaves or cover-sections a and a' may have the appearance of the covers of a book, the various corners of said sections a and a' may be rounded off, as at a^{11} , and the various 10 sides and edges of the said sections may be provided with a leather or other suitable covering d , which is secured to the metal surfaces of said sections a and a' in any well-known manner. It will, however, be understood 15 that the said covering d may be dispensed with, if desired, and that the exposed metal surfaces of said leaves or sections a and a' may be otherwise ornamented. The said receiving device hereinabove mentioned, 20 which is to be used in connection with the said leaves or cover-sections a and a' , is indicated by the reference-letter c . It is made of sheet metal, and consists, essentially, of the body c' and the upwardly-extending sides 25 c^3 at the ends and a connecting side c^4 at one edge of said body, the other edge c^2 of said body being made without such upwardly-projecting side, as clearly illustrated in Fig. 9.

The upper corners of the sides c^3 are preferably cut away, as at c^{11} , and centrally disposed upon the upper edge of the side c^4 and forming an integral part thereof is an upwardly-extending tongue or ear c^6 , which is formed, by means of a suitable die, with the 30 rounded portion c^7 and the forwardly-bent edges c^8 , which extend beyond the outer surface c^9 of the side c^4 , and hence form a pair of holding portions c^{10} , which can be forced over the connecting portion or band-like part 35 c^8 of the leaf or cover-section a' when the device is secured in position upon the leaf or cover-section a and when the said cover-section a' is closed down upon said device c . To secure said device c upon said cover-section 40 a , I have provided the main body portion c' of the device c with one or more slots or openings c^5 , through which the holding tongues or lugs c^6 , connected with the said holding leaf or section a , can be forced and then bent over 45 upon the face of said device c , as clearly illustrated in Fig. 3, to securely retain the said receiving device c in position. When these parts have thus been connected, the inner surface of the right-angled wall a^2 will form 50 one side of the box or receptacle between the leaves or cover-sections a and a' , as will be clearly understood from an inspection of Figs. 3, 4, and 5.

To open the case or box and to cause the 55 disengaged positions of the holding portions c^{10} with the upper surface of the band-like part c^8 of the leaf or cover-section a' , all that is necessary is to apply a slight pressure against the outer surface of the side c^4 of the device c in the direction of the arrow x in 60 said Fig. 7, and a slight upward pressure in

the direction of the arrow x' will permit of the pivotal motion of the cover-section a' , and hence the opening of the box or case.

From the above description it will be seen 70 that I have devised a simple and cheaply-constructed device which is neat in appearance and is well adapted to accomplish the results for which it is intended.

Of course it will be understood that changes 75 may be made in the several arrangements and combinations of the various parts as well as in the details of the construction thereof without departing from the scope of my present invention. Hence I do not limit my invention 80 to the exact arrangements and combinations of the various parts as herein described, and illustrated in the accompanying drawings, nor do I confine myself to the exact details of the construction of the various parts. 85

Having thus described my invention, what I claim is—

1. In a box or case, the combination, with a pair of leaves or cover-sections, one of said cover-sections having a right-angled edge or 90 wall, and a pivotal connection between said edge or wall and the other of said cover-sections, of a receiving device, between said cover-sections, said device having three inclosing sides and one open side, said inclosing 95 sides of said device forming with said right-angled edge or wall of the cover-section on which said device is arranged, a receptacle, substantially as and for the purposes set forth.

2. In a box or case, the combination, with a pair of leaves or cover-sections, one of said cover-sections having a right-angled edge or wall, and a pivotal connection between said edge or wall and the other of said cover-sections, of a receiving device, between said 105 cover-sections, said device having three inclosing sides and one open side, said inclosing sides of said device forming with said right-angled edge or wall of the cover-section on which said device is arranged, a receptacle, 110 and a fastening means connected with said leaf or cover-section on which said receiving device is arranged, constructed to engage with said device for securing it in position, substantially as and for the purposes set forth. 115

3. In a box or case, the combination, with a pair of leaves or cover-sections, one of said cover-sections having a right-angled edge or wall, and a pivotal connection between said edge or wall and the other of said cover-sections, of a receiving device, between said cover-sections, said device having three inclosing sides and one open side, said inclosing 120 sides of said device forming with said right-angled edge or wall of the cover-section on which said device is arranged, a receptacle, and a fastening means connected with said leaf or cover-section on which said receiving device is arranged, constructed to engage with said device for securing it in position, consisting, essentially, of holding lugs or ears formed integral with said leaf or cover-section, and 125 130

extending into openings or slots in said receiving device and bent over, substantially as and for the purposes set forth.

4. In a box or case, the combination, with a leaf or cover-section, having an upwardly-extending holding prong or prongs, of a box-shaped receptacle on said section provided with an opening or openings, in which said prong or prongs are arranged and bent over, substantially as and for the purposes set forth.

5. In a box or case, the combination, with a box-shaped receptacle, and an upwardly-extending tongue or ear c^6 on the edge of one side of said receptacle, provided with a pair of forwardly-extending edges c^8 having holding portions c^{10} , of a leaf or cover-section connected with said receptacle and provided with an opening a^7 and a band portion a^8 with which said holding portions c^{10} can be brought in locked engagement, substantially as and for the purposes set forth.

6. In a box or case, the combination, with a pair of leaves or cover-sections a and a' , one of said sections, as a , having a right-angled edge or wall, a pivotal connection between said edge or wall and said section a , said section a' being provided with an opening a^7 and a band portion a^8 of a box-like receptacle c between said sections a and a' , said receptacle c having three inclosing sides, as c^3 and c^4 , and one open side, said inclosing sides of said receptacle forming with said right-angled edge or wall of the section a a box-like receptacle, and an upwardly-extending tongue or ear c^6 on the upper edge of said side c^4 , provided with a pair of forwardly-extending edges c^8 having holding portions c^{10} which can be brought in holding engagement with said band portion a^8 of said section a' , substantially as and for the purposes set forth.

7. In a box or case, the combination, with a pair of leaves or cover-sections a and a' , one of said sections, as a , having a right-angled edge or wall, a pivotal connection between said edge or wall and said section a' , said section a' being provided with an opening a^7 and a band portion a^8 of a box-like receptacle c

between said sections a and a' , said receptacle c having three inclosing sides, as c^3 and c^4 , and one open side, said inclosing sides of said receptacle forming with said right-angled edge or wall of the section a a box-like receptacle, and an upwardly-extending tongue or ear c^6 on the upper edge of said side c^4 , provided with a pair of forwardly-extending edges c^8 having holding portions c^{10} which can be brought in holding engagement with said band portion a^8 of said section a' , and a fastening means connected with said section a constructed to engage with said receptacle c and hold it in position, substantially as and for the purposes set forth.

8. In a box or case, the combination, with a pair of leaves or cover-sections a and a' , one of said sections, as a , having a right-angled edge or wall, a pivotal connection between said edge or wall and said section a' , said section a' being provided with an opening a^7 and a band portion a^8 , of a box-like receptacle c between said sections a and a' , said receptacle c having three inclosing sides, as c^3 and c^4 , and one open side, said inclosing sides of said receptacle forming with said right-angled edge or wall of the section a a box-like receptacle, and an upwardly-extending tongue or ear c^6 on the upper edge of said side c^4 , provided with a pair of forwardly-extending edges c^8 having holding portions c^{10} which can be brought in holding engagement with said band portion a^8 of said section a' , and a fastening means connected with said section a constructed to engage with said receptacle c and hold it in position, consisting, essentially, of holding lugs or ears formed integral with said section a , and extending into openings or slots in the body portion of said receptacle c and bent over, substantially as and for the purposes set forth.

In testimony that I claim the invention set forth above I have hereunto set my hand this 9th day of June, 1899.

BURKARD ROSEN BAND.
